Attorney,

UNITED STATES PATENT OFFICE.

WILLIAM P. PREWITT, OF ELKTON, KENTUCKY, ASSIGNOR TO HIMSELF AND CALEB W. BELL, OF SAME PLACE.

RAILWAY-CAR.

SPECIFICATION forming part of Letters Patent No. 252,855, dated January 24, 1882.

Application filed December 7, 1881. (No model.)

To all whom it may concern:

Be it known that I, WILLIAM P. PREWITT, of Elkton, in the county of Todd and State of Kentucky, have invented certain new and useful 5 Improvements in Railroad-Cars; and I do hereby declare that the following is a full, clear, and exact description thereof, reference being had to the accompanying drawings, and to the letters of reference marked thereon, which 10 form part of this specification, in which—

Figure 1 is a plan view, and Fig. 2 a side elevation, part in section.

The frequency with which brakemen upon the top of freight-trains fall between the cars 15 and become either seriously injured or instantly killed has become a well-grounded cause of complaint.

The object of my invention is to provide a safe and simple means whereby such disasters 20 may be entirely obviated, and one, withal, which will be an advantage to the cars, as it will assist in lessening the concussion of one against the other, which is more or less the case in stopping.

25 With these ends in view my invention consists in having two or more rods projecting through or from the end of each car, and around which are suitable spiral springs, said springs being connected by wire, rope, or other appropriate material, all as will be hereinafter more fully set forth.

To enable others skilled in the art to make and use my invention, I will now proceed to describe the manner in which I prefer to carry 35 it into effect.

A A represent two freight-cars, and B B two rods of sufficient size to adapt them to the purpose for which they are intended. These rods are headed upon their outer end, and pass 40 through the end of a car, on each side, a foot (more or less) below its top, as shown in the drawings.

C C are supports or guides attached to the inner side of the car for the rods B B to slide 45 in and retain them in proper position. Between the outer end of the car and the heads on the rods are the spiral springs b b. These

springs should be of sufficient strength to assist in breaking the concussion of the cars when stopping; or, if not desired for that purpose, they may only possess elasticity sufficient to keep the rods extended when relieved from pressure.

a a indicate wire, rope, or any other suitable material, which connect the two springs 50 in such manner as will prevent a man from falling below them; or, in other words, these wires or ropes are intended, in the event of a brakeman falling between the cars, to catch and sustain him until he can recover his foot- 55 ing.

e represents a chain with small links, through which the wires a a pass at their centers. This chain is secured on the inner side of the car, and serves to prevent the wires or ropes 60 getting too widely separated.

The rods B B are also provided at their inner ends with means to prevent them from being drawn out, as seen at g, Fig. 2.

Having thus fully described my invention, 70 what I claim, and desire to secure by Letters Patent, is—

1. The combination, with a railroad-car, of two sliding or retracting supports surrounded by spiral springs, to which are secured cross-supports, thus adapting said supports to close up or open out, substantially as and for the purpose described.

2. The combination, with a railroad-car, of the rods B B, surrounded by spiral springs 80 b b, and rods or connections a a, all substantially as and for the purpose set forth.

3. The combination, with a railroad-car, of rods B B, springs b b, connections a a, and chain e, all arranged to operate substantially 85 as and for the purpose set forth.

In testimony that I claim the foregoing as my own I affix my signature in presence of two witnesses.

WM. P. PREWITT.
